Primary Examiner — R. Johnson(74) *Attorney, Agent, or Firm* — BOND, SCHOENECK & KING, PLLC; George R. McGuire(57) **CLAIM**

The ornamental design for a tool for changing strings on a stringed instrument as shown and described.

DESCRIPTION

FIG. 1 is a perspective view of a new and ornamental tool for changing strings on a stringed instrument;

FIG. 2 is a front elevation view thereof;

FIG. 3 is a rear elevation view thereof;

FIG. 4 is a first side elevation view thereof;

FIG. 5 is a second side elevation view thereof;

FIG. 6 is a top plan view thereof; and,

FIG. 7 is a bottom plan view thereof.

The internal features are being shown in broken lines throughout the drawings to illustrate environment and form no part of the claimed design.

1 Claim, 6 Drawing Sheets(56)
